UNITED STATES PATENT OFFICE.

FERDINAND J. TILLMAN AND ALFRED C. TILLMAN, OF ST. LOUIS, MISSOURI; SAID ALFRED C. TILLMAN ASSIGNOR TO SAID FERDINAND J. TILLMAN.

CALCULATING ATTACHMENT FOR TYPEWRITERS.

Application filed January 23, 1919. Serial No. 272,612.

To all whom it may concern:

Be it known that we, FERDINAND J. TILLMAN and ALFRED C. TILLMAN, citizens of the United States of America, and residents 5 of the city of St. Louis, and State of Missouri, have invented certain new and useful Improvements in a Calculating Attachment for Typewriters, of which the following is a specification.

10 This invention relates to improvements in the mechanisms of calculating attachments for typewriters, one of the objects being to provide an improved way of selecting the accumulator or accumulators to be calculated on by arranging means adjacent the rear of the typewriter carriage, and also a reverse order of means under the control of the operator adjacent the front of the typewriter to change the selection of the 15 accumulator or accumulators regardless of the arrangement of the means adjacent the rear of the typewriter carriage.

Another object of this invention is in providing means for operating the calculating 20 mechanisms upon the downward stroke of a numeral key of the calculating device, thereby allowing another numeral key to be operated before the first operated key has returned to its normal position.

25 A further object is in providing improved locking and unlocking means which are operated on the downward stroke of a numeral key so as to prevent a second or more keys being operated while the operated key is on its downward stroke, and incidentally during the operation of calculating, said means also providing for releasing the locked position of the other keys just before the operating key has reached the limit 30 of its downward stroke, thereby allowing another key to be operated before the first operated key returns to its normal position.

35 A still further object is in providing means for allowing all of the numeral keys 40 of the same stroke of travel relative to counting regardless of the value of the key selected and operated.

45 Another still further object is in providing an improved locking mechanism relative to the adding and subtracting mechanisms that is operated in conjunction with another locking mechanism.

Other and further objects will appear in the specification and be specifically pointed out in the appended claims, reference being 55 had to the accompanying drawings exemplifying the invention, and in which,

Figure 1 is a longitudinal section taken through this improved calculating attachment, showing its relation to a typewriter 60 mounted thereover.

Figure 2 is a fragmentary horizontal section taken approximately on the line II—II of Fig. 1.

Figure 3 is a transverse section taken 65 approximately on the line III—III of Fig. 1.

Figure 4 is a fragmentary transverse section taken on the line IV—IV of Fig. 2.

Figure 5 is a fragmentary transverse section taken on the line V—V of Fig. 2.

Figure 6 is a fragmentary longitudinal section taken approximately on the line VI—VI of Fig. 2.

Figure 7 is a fragmentary longitudinal 75 section taken approximately on the line VII—VII of Fig. 2.

Figure 8 shows a group of the tabulating stops used on the tabulator rack in connection with this improved calculating attachment.

Figure 9 is an enlarged horizontal section of the left-hand portion of Figure 6.

Referring to the drawings, a rectangular supporting frame 1 is provided for enclosing 85 the greater portion of this improved calculating attachment, the typewriter 2 to which the calculating attachment is adapted to be co-operable being mounted on said frame 1.

90 Removably secured to each of the numeral keys 3 of the typewriter is a link 4, each of said links at their lower ends being pivotally connected to a respective calculating key 5, said keys 5 being reciprocally mounted in 95 a pair of horizontal supports 6 and 7 which are secured to the side walls 8 and 9 of the frame 1, and carried by each of said keys 5 are a pair of spaced apart pins 10 and 11. Arranged between each of said pins of 100 each key is one end of a segmental lever 12, each of said levers being respectively pivot ed at 13 to a respective supporting bracket 14, all of said brackets 14 being turnably

mounted as designated at 16 to a cross bar 17, the pivots 13 of said brackets being out of alinement with one another so that the circumferential travel of the teeth bearing ends 18 of said segmental levers 12 will be of different lengths.

As shown in Fig. 2, each segmental lever 12 of which there are nine is adapted to co-operate with a respective gear 19, said 10 gears being rigidly secured to a horizontally arranged accounting transmission shaft 20, said shaft being supported at its ends in the side walls 8 and 9 of the frame 1.

Rigidly secured to said shaft 20 adjacent 15 the side wall 8 is a transmission gear 21 meshing with a matching gear 22 which is slidably mounted on the master wheel shaft 23. Formed on the master wheel shaft 23 is a longitudinal key-way 24 which provides 20 for slidably keying the gear 22 thereto. Rigidly secured to the shaft 20 is a gear 25, said gear being of the same diameter as the gears 21 and 22, and meshing with said gear is a reversing pinion 26 which is 25 mounted on a stub shaft 27, said stub shaft being supported from the wall 8, said pinion 26 being in sliding alinement with the gear 22 of the master shaft, and is adapted to co-operate with said gear 22 when said gear 30 is placed in mesh therewith by the shifting lever 28.

Slidably mounted on the master wheel shaft 23 is a master wheel 29 which is adapted to co-operate with the mechanisms of 35 the grand totalizer accumulator 30, said wheel 29 having the annular groove 31 of its hub in engagement with a depending support 32.

Oppositely disposed from said support 32 40 is a support 33 having its upper end in sliding engagement with the master shaft 23, and swingingly mounted between said supports 32 and 33 is a rack 34 having a pair of forwardly extending ears 35, and mounted between said ears is a tilting bar 36 which parallels the rack 34. Engaging said tilting bar 36 is the bifurcated end 37 of a shifting lever 38, said lever being pivoted at 39 to a bracket 40 which is supported by 45 the front plate 41 of the frame 1.

The supports 32 and 33 are slidably mounted on a horizontally arranged guiding member 42, said guiding member being supported at its ends in the walls 8 and 50 9 of the frame 1. Slidably mounted on the master wheel shaft 23 is another master wheel 43 which is adapted to co-operate with the mechanisms of the cross figure accumulator 44, and in engagement with each 55 annular groove 45, a pair of which are formed on the hub of the master wheel 43, are the bifurcated ends 46 of a rack support 47, and swingingly secured at 48^a to the lower end of said support is a rack 48. Forwardly extending from said rack 48 are a

pair of ears 49, and carried by said ears is a tilting bar 50 which parallels said rack 48.

In engagement with said tilting bar 50 is the bifurcated end 51 of a shifting lever 52, said lever being pivoted at 53 to the bracket 40, and embracing said lever 52 and the lever 38 is a quadrant 54 containing locking notches 55 and 56; the lever 52 being co-operable with the notches 56, 75 whereas the lever 38 is co-operable with the notches 55.

Mesning with the rack 48 are teeth 57 of a segmental gear 58, and arranged opposite from said teeth 57 on said gear are 80 teeth 59, said gear 58 being turnably mounted on the bolt 60 which is carried by a cross member 61, which is arranged between the side walls 8 and 9 of the frame 1.

Turnably mounted on said bolt 60 beneath the segmental gear 58 is another segmental gear 62, the teeth 63 of which are adapted to mesh with the teeth of the rack 34.

Oppositely disposed on said gear 62 from 90 the teeth 63 thereof is another set of teeth 64, said teeth being in mesh with the teeth of a gear segment 65 that is rigidly secured to the lower end of a vertically arranged shaft 66, said shaft 66 being mounted in a tubular shaft 67, the lower end of said shaft 67 having a gear segment 68 rigidly secured thereto, the teeth of said segment 68 being in mesh with the teeth 59 of the segmental gear 58.

Bearings such as 69 are provided for the support of the tubular shaft 67, said tubular shaft along with the shaft 66 contained therein being arranged vertically adjacent the rear of the typewriter 2.

Secured to the upper end of the shaft 66 is a crank 70 carrying a spring held dog 71, said dog being pivoted to said crank 70 and arranged in the path of travel of the tabulating stops 72 that are removably mounted on the tabulator rack 73, the spring of said dog being secured thereto and to said crank, and carried by said crank is a limiting pin so that the spring of said dog will normally hold it against said pin. Secured to the upper end of the tubular shaft 67 is a crank 74 carrying a swingingly mounted spring actuated dog 75, said dog 75 and its actuating spring being secured to the crank 74 in a like manner as is the dog 71 and its respective spring to the crank 70, said dog also being in the path of travel of the tabulating stops 72.

Secured to the rear wall 76 of the frame 1 are a pair of brackets 77 supporting a horizontally arranged shaft 78, and secured to one end of said shaft is a locking member 79 which depends downwardly from said shaft, and is adapted to engage between the teeth 59 and 64 of the segmental gears 125 130

58 and 62, respectively. Secured at one end said locking member 79, and at its opposite end to the wall 76 is a coil spring 80 which tends to normally hold said locking 5 member out of locking position.

Carried by the opposite end of the shaft 78 is a lever 81 to which is secured one end of a shifting rod 82, the opposite end of said rod extending to the forward end 10 of the frame 1, said rod adjacent its forward end being pivotally secured at 83 to a ratchet pawl 84, said pawl being swingingly secured at 85 to the side wall 8 of the frame 1, said pawl being adapted to 15 engage the teeth of a locking ratchet wheel 86, which is rigidly secured to the transmission shaft 20.

The forwardly extending end 87 of the shifting rod 82 is mounted in the guiding 20 portion 88 of the support 89 of the shifting lever 28. Extending upwardly from the shifting rod 82 adjacent its forward end 87 is a locking projection 90 which is adapted to co-operate with a portion 91^a of 25 a shifting plate 91 of the gear shifting member 92, which is co-operable with the lower end of the shifting lever 28 of the gear 22.

Carried by the shifting rod 82 intermediate of its ends is a horizontally extending pin 93, and engaging said pin is a bifurcated end 94 of a swingingly mounted double actuating lever 95 which is swingingly secured at 96 to the side wall 8. Oppositely disposed from said lever 95, and swingingly secured to the side wall 9 is a mating lever 97, said levers 95 and 97 supporting a transversely and horizontally arranged pusher bar 98. Supported by the walls 8 and 9 40 and paralleling the bar 98, and arranged there above, is a supporting member 99, and swingingly depending from said member are a plurality of spaced apart cams 100, each cam being slidably mounted in a vertical 45 slot 101, which is formed in the cross member 102, said cross member being supported by the horizontal supports 6 and 7 which are secured to the walls 8 and 9 of the frame 1.

50 Arranged beneath the lower ends of the cams 100 is a supporting member 103, carrying a plurality of spaced apart swingingly mounted locking members 104, each of said members being mounted in a vertical slot 105, said slots 105 being formed in the cross member 102.

For tending to hold the cams 100 and the locking members 104 inwardly, a coil spring 106 engages pairs of cams and locking members together. Arranged horizontally and rearwardly of the cams 100, and swingingly mounted on a horizontal support 107 are a plurality of crowding members 108 which comprise a crowding out system for forming a key-lock, said members

being arranged in pairs, the adjacent abutting faces thereof forming approximately V-shaped recesses 109, and there being a pair of members 108 relative to each cam 100, the outer arranged members 108 being 70 coupled by a yoke 110.

From an inspection of Fig. 2, it is to be noted that the segmental levers 12 are normally out of mesh with their respective gears 19, and in which position the rear ends of 75 said levers are in inactive positions and are on what may be termed the return sides of the guiding plate 114.

In carrying out the operation of this improved calculating attachment, when a typewriter has been mounted on the frame 1 of the calculating attachment, and the links 4 connected to the numeral keys 3 of the typewriter, as described, when a numeral key 3 of a typewriter is operated, a respective 80 calculator key 5 coupled therewith will be depressed, thereby carrying down the cam 111, one of which is carried by each calculating key, and the bevelled face of which is formed on a plane lower than the pin 10 90 of each key, said cam engaging the rear end of a respective lever 12, thereby forcing the rear end of said lever over to one side, and causing the bracket 14, to which said lever is pivotally secured, to swing on its pivot 16 95 to a position of engagement against a respective stop 112, and in which moved position the teeth bearing end of said lever 12 will be placed in an alining position relative to engaging the teeth of a respective 100 gear 19 of the accounting transmission shaft 20.

Upon moving the rear end of the segmental lever 12 to the position as just described relative to the actuation of the cam 111 105 there against, it is to be noted that the rear end of said lever was moved to a vertically alined position relative to the cam surface portion 113 of a respective cam 100, and to the opposite side of the respective 110 guiding plate 114, and in this position, inasmuch as the cam 111 of the operated calculator key 5 has been disengaged from engagement with the segmental lever 12, the pin 10 carried by said key 5 will engage 115 said lever, and force it downward, the extreme rear end of said lever bearing against the cam surface 113, thereby forcing the rear end 115 of said cam 100 in between a respective pair of crowding members 108, 120 thereby providing a two-key lock action that will be hereinafter described. Incidental with the downward travel of the rear end of the elected segmental lever 12 just mentioned, the teeth of the teeth bearing end 125 thereof were elevated, thereby engaging and meshing with the teeth of the respective gear 19 to which said lever 12 is related, and imparting motion to the transmission shaft 20 on which said gear is mounted, which 130

motion will be transferred from said shaft 20 through the gears 21 and 22 to the master wheel shaft 23, thereby imparting the proper amount of motion to said shaft relative to the action of the number of teeth called for on the operated segmental lever 12, and in which either one or both of the master wheels 29 and 43 will be actuated relative to actuating either one or both of the accumulators 30 and 44, as called for by the operator.

After the afore mentioned segmental lever 12 has reached the end of its downward travel, and the motion of the teeth bearing end 18 of said lever has been transferred to the master wheel shaft and accumulators as just described, the coil spring 116, one of which is related to each supporting bracket of each segmental lever will become active on account of the rear end of said lever in its downward position being beneath the lower end of the guiding plate 114, and pull the teeth bearing end 18 of said operated lever out of mesh from its respective gear 19 which has just been operated, said pulling out movement simultaneously returning the rear end of said lever to the inactive side of the guiding plate 114, and inasmuch as the operator's finger 114, has been released from the typewriter key, the return spring 117 of said lever will return the rear end of the lever to its upwardly normal position, and incidentally the teeth bearing end of said lever will be lowered.

If during the upward travel of the rear end of the segmental lever 12 the operator through carelessness or otherwise again operated the numeral key of the typewriter in which the calculating key 5 would tend to be forced downward, the extreme rear end of said lever on its downward movement would engage one of the teeth 118 of the swinging locking member 104 as said locking member is resiliently held in the path of travel of the rear end of said lever.

The pins 11, one of which is carried by each calculating key 5 is provided for the purpose of preventing the keys from being returned before completion of their stroke or operation.

Referring now to the two-key locking means which became active as the swinging cam 100 was moved rearwardly by the descending segmental lever 12, the rear end 115 of said cam 100 upon being forced further in to its respective V-shaped recess 109, forced the co-relating pair of crowding members 108 apart, thereby crowding the rest of said members 108 together, thereby presenting a solid body through the entirety of the remaining members 108, in which no other swingingly mounted cam 100 would be allowed to be moved rearwardly in the event of the operator attempting to operate a sec-

ond key before the first key operated had completed its downward travel.

Immediately on completion of the downward stroke of the operated key and before said lever is moved to the opposite side of the guiding plate 114, the rear end of said lever became released from engagement with its respective swinging cam 100, thereby allowing the return spring 106, which is related to said cam to swing said cam forwardly, thereby withdrawing the rear end 115 of said cam from engagement between the pair of crowding members 108, and leaving all of the crowding members 108 in receptive positions ready for the operation of a second key, which second operation can be carried on while the first operated lever 12 is returning to its neutral position. It is therefore to be noted that with such a construction a rapidly operating machine is provided, as it is not necessary to wait for the complete return of a previously operated key before operating a second key.

Co-incident with the rearward movement of any cam 100 relative to a respective lever 12 operated, three other locking actions are brought into effect which are the adding and subtracting shifting lever lock, transmission shaft lock, and platen carriage lock, said locking actions being carried on as follows: When any one of the plurality of swinging cams 100 is moved rearwardly by the actuation of a typewriter key and its related calculating key, the bar 98 arranged rearwardly of said cams 100 will cause the lower end of the lever 95 to move forwardly, thereby forwardly moving the shifting rod 82, and inasmuch as the ratchet pawl 84 is pivotally connected to said shifting rod, said pawl will be disengaged from the locking ratchet wheel 86 which is carried by the transmission shaft 20, thereby unlocking and allowing said shaft to be moved in a calculating direction from actuation of the key being operated.

During the forward movement of the shifting rod 82, the locking projection 90, which is carried by said rod adjacent the forward extending end 87 thereof will engage the abutting portion 91a of the shifting plate 91 and gear shifting member 92, which is co-operable with the shifting lever 28 of the gear 22, thereby preventing the gear 22 from being shifted from out of mesh with the gear 21 of the transmission shaft 20.

The meshing position of the gears 21 and 22 as shown in Fig. 2 denotes that the master wheel shaft 23 is travelling in an adding direction relative to the accumulators, whereas when it is desired to provide a subtracting action to said master wheel shaft 23, the operator will actuate the lever 28, thereby moving the shifting plate 91 and sliding the gear 22 on its shaft and out of mesh with the gear 21, and into mesh with the revers-

75

105

110

115

120

125

130

ing gear 26, said gear 26 being constantly in mesh with the gear 25 which is carried by the transmission shaft 20. In this shifted position of the plate 91, the abutting portion 91^a is carried to a position across the forward end 87 of the shifting rod 82, in which position the shifting plate will be held against return movement by the projection 90 of said shifting rod 82 being in the path 10 of the portion 91^a when said shifting rod is moved forward as just related relative to releasing the ratchet pawl 84.

In addition to the aforesaid moving forward of the shifting rod 82, since the rear 15 end is secured to the lever 81 of the shaft 78, which is supported from the end wall 76 of the frame 1, the locking member 79 carried by said shaft 78 which is normally held in a rearward moved position is moved forward, thereby engaging the teeth 59 and 64 20 of the segmental gears 58 and 62, thereby locking the master wheels 29 and 43 of the master wheel shaft 23 and the typewriter carriage A against horizontal movement.

25 From the aforesaid description relative to the three locking features just described, it is quite obvious that when any calculating key is operated downwardly, the shifting rod 82 actuated therewith will incidentally release the transmission shaft 20 so that it can be moved in the calculating direction, and at the same time prevent the shifting gear 22 from being moved out of either an adding or subtracting position during the 30 downward stroke of the key operation, and in addition lock the platen carriage A and master wheels 29 and 43 against horizontal movement so that the said master wheels cannot be moved out of their selected 35 accounting columns of their respective accumulators.

Upon completion of the downward stroke 40 of a calculating key and just before the returning of the actuated calculating key has commenced as afore related, the swinging cam 100, which is moved rearward by the downward key operation immediately swings forward, thereby allowing the cross bar 98 to move forward, which will cause the shifting rod 82 to move rearward, thereby 45 affecting the lock on the transmission shaft 20 and releasing the adding and subtracting shifting mechanism, and also releasing the lock pertaining to the carriage and master 50 wheels so that they can be shifted to any desired column, which will be predetermined by the operator.

55 In describing the operation of the master wheel shifting mechanism which is comprised of the segmental gears 58 and 62, racks 34 and 48 at one end, and the gear segments 65 and 68, the operator having previously mounted a tabulating stop 72 in the desired position on the tabulator rack 58 60 65 73 which is carried by the platen carriage A,

then the tabulating key 118, upon being operated will cause the member 119 to release the carriage A and allow it to travel to a position until stopped by the engagement of stop 72 with one of the stop dogs 70 75 120 which has been moved into stopping position by the tabulator key 118.

As the rack 73 and tabulator stop 72 carried thereby travelled, the projection 121 of said stop 72 engaged against the dog 75 of 75 the crank 74, thereby moving said crank and tubular shaft 67 on which said crank is mounted, and causing the gear segment 68 to impart motion to the segmental gear 58, and inasmuch as the teeth 57 of said gear 80 58 are in mesh with the rack 48, which is carried by the support 47 of the master wheel 43, said master wheel will be shifted to a corresponding position relative to the position of stopping of the tabulator stop 85 72 which will provide the desired denomination required in the accumulator 44 to which the master wheel 43 pertains.

In operating the master wheel shifting mechanism pertaining to the accumulator 90 30, a tabulator stop such as 122, having an over hanging depending portion 123 see Fig. 8, is mounted in the desired position on the rack 73, said depending portion 123 during the travel of the stop 122 engaging and 95 moving the dog 71 which is carried by the crank 70, said crank being secured to the upper end of the shaft 66, and at its lower end to the gear segment 65, and since said segment 65 is in mesh with the segmental 100 gear 62, the rack 34 will be moved, thereby moving the supporting member 32 and shifting the master wheel 29 to a position corresponding with the position of the tabulator stop 122 so that said master wheel will 105 be in position to transfer calculating movement to its accumulator 30 dependent on the calculator key operated.

If it is desired to move both of the master 110 wheels 29 and 43 at one time into like positions relative to their respective accumulators to which they are adapted to co-operate, a tabulating stop such as 124, having the vertical extending portion 125, is predeterminedly mounted on the rack 73, then when 115 the carriage is released by actuation of the tabulating key 118, the vertical portion 125 of said stop 124 will engage and move both of the dogs 75 and 71, thereby transmitting motion to both of the segmental gears 58 120 and 62, and to both of the racks 34 and 48, and their respective master wheels.

Inasmuch as both of the dogs 71 and 75 are spring actuated, when the carriage A is returned, it will pass by the tabulating 125 stops carried by the carriage and will pass said dogs without becoming active on the master wheel shifting mechanism, as the master wheels 29 and 43 and their shifting mechanisms pertaining thereto are returned 130

to their neutral positions by the springs 126 and 127, which are operable with respective rack supports of the master wheels 29 and 43. If however, any one of the tabulator stops have been set in a predetermined position on the rack 73, and it is desired by the operator to change the order of working of a certain specific stop, for instance if the stop 72 has been set, and it is desired to 5 make said stop do the work of tabulator stop 122, said stop 72 being primarily intended to actuate the segmental gear 58 and master wheel 43, the operator on moving the lever 52 forward will swing the rack 48 upwardly out of meshing relation with segmental gear 58. The lever 38 is then pulled rearwardly, thereby swinging lower rack 34 upwardly and in mesh with the teeth 57 of the gear 58, in which position the tabulator 10 stop 72 when moved by the carriage A will shift the master wheel 29.

On the other hand if it is desired to make the tabulator stop 122 do the work that is primarily intended for the stop 72, the lower rack 34 is thrown out of mesh from the segmental gear 62 by actuation of the shifting lever 38, then the upper rack 48 is shifted by its lever 52 into mesh with the teeth 63 of the gear 62, thereby making the master 15 wheel 43 co-operable with the movement of the segmental gear 62. It is to be noted that the teeth of the racks 34 and 48 are wider than their co-operating segmental teeth of the segmental gears 58 and 62. This is for 20 the purpose of adapting either one of the racks to a double engagement with both of the sets of teeth of said segmental gears 58 and 62, as it is sometimes desired to shift both of the master wheels 29 and 43 to the 25 same denominating position to their respective accumulators, without the aid of the tabulator stop 124. In this connection, on account of the levers 38 and 52 being located at the front of the machine, the operator can 30 readily shift either of said levers, thereby disregarding the previously set position of either of the tabulator stops 72 or 122.

Each of the segmental gears is provided with a special tooth 128, each tooth being adapted to mesh with a special recess of each rack 34 and 48, each of said racks being further provided with a special tooth 129, said teeth 129 being co-operable with a respective segmental gear 58 and 62, said 35 special teeth 128 and 129 providing a lock, so that said racks can not engage the teeth of the segmental gears in improper positions, when being swung into engagement with either of said segmental gears.

As shown in Figs. 1 and 2, the segmental levers 12 which have their pivots 13 to the right of the cross bar 17 are each guided in their vertical swinging movement between vertical pairs of upwardly extending members 129, each pair of members 129 forming

part of each respective bracket 14. These pairs of members 129 relieve the horizontal swinging strain of the levers 12 from their respective pivots 13 when said levers are shifted in and out of mesh from their respective gears 19 relative to said levers swinging on their pivots 16, and to throw the swinging strain of said levers on said pivots 16.

What we claim is: —

1. In a calculating machine, a calculating mechanism, a plurality of calculating keys, each adapted to the same distance of travel, and a transmission mechanism comprised of a plurality of intermediately pivoted, horizontally and vertically swingable members which are continually in mesh with the gearing of said calculating mechanism during the downward stroke of said keys. 75

2. In a calculating machine, a plurality of calculating keys, a pivoted lever for each of said keys, each bearing a sector, a swivel support for each of the pivots of said levers, and a transmission shaft bearing gearing, said sectors of said levers being continually 90 co-operable with said transmission shaft and said keys during the downward stroke of said keys. 80

3. In a calculating machine, a plurality of calculating keys, a calculating mechanism, and a transmission mechanism comprised of a plurality of levers each being differently fulcrumed and adapted to both vertical and horizontal swinging movement, co-operable with said keys and said calculating mechanism for providing a continual transmitting movement to said calculating mechanism during the complete downward travel of any one of said keys. 95

4. In a calculating machine, the combination of a plurality of calculating keys, a plurality of swinging levers each having their respective pivots differently positioned, swivel supporting means for said pivot of said levers, and a transmission mechanism, said keys and said mechanism being directly co-operable with each other by said levers so that said transmission mechanism will be continually operated during the downward movement of any one of said keys. 105

5. The combination of a calculating mechanism and a typewriter co-operable therewith, said mechanism having a plurality of calculating keys which are coupled with the numeral keys of the typewriter, a lever related to each of said keys, each having its pivot differently located, a swivel support for each of the pivots of said levers, and a transmission mechanism forming part of the calculating mechanism coupled with each of said calculating keys by said levers adapted to continual operation during the complete downward travel of any one of said calculating keys. 110

6. In a calculating machine, a calculating

key, a transmission gear, and a pivoted segmental gear having one end operably related with said key, and its opposite end co-operable with said gear and there being a swivel support for the pivot of said lever.

7. In a calculating machine, a calculating key, a transmission gear, and a pivoted segmental gear having one end operably related with said key, and its opposite end co-operable with said gear, and means provided for withdrawing said lever from meshing with said gear.

8. In a calculating machine, a segmental gear having a lever and adapted to a vertical and a horizontal swinging movement, a calculating key operable with said lever, a gear adapted to be actuated by said segmental gear, and means provided for withdrawing said segmental gear from engagement 20 with said other gear.

9. In a writing machine, the combination of a platen carriage bearing a rack bar, a master wheel, a removable tabulator stop carried by said rack bar, a shifting mechanism for said master wheel comprised of geared means which are operable by said stop, and a shiftable rack movable with said master wheel adapted to be placed in or out of mesh with said geared means.

30 10. In a writing machine, the combination of a platen carriage bearing a rack bar, a master wheel, a removable tabulator stop carried by said rack bar, a shifting mechanism for said master wheel comprised of 35 a pair of independently movable geared means either of which are adapted to be actuated by said stop, and a shiftable rack movable with said master wheel adapted to be placed in mesh with either of said geared means.

11. In a writing machine, the combination of a platen carriage bearing a rack bar, a master wheel, a removable tabulator stop carried by said rack bar, a shifting mechanism for said master wheel comprised of a pair of independently movable geared means either of which are adapted to be actuated by said stop, and a shiftable rack movable with said master wheel adapted to mesh 50 simultaneously with both of said geared means.

12. In a calculating attachment for a typewriter, a master wheel shiftably relative to the shaft on which it is mounted, a rockable 55 rack member movable with said wheel, a platen carriage forming part of the typewriter to which the calculating mechanism is related, geared means co-operable with said rack member and said carriage for shifting said wheel when the carriage is moved, and other means for disengaging said rack member from engagement with said geared means.

13. In a calculating machine, a pair of 60 master wheels, a pair of movable members

each adapted to shift said wheels independently of one another, and there being means provided for allowing said members to be operated in unison so as to become active towards shifting both of said wheels together.

70 14. The combination of a typewriter and a calculating machine, a master wheel shifting mechanism comprising a pair of swinging members forming part of said calculating machine operable with the carriage of the typewriter, a pair of master wheels adapted to be actuated by said members, and means provided whereby either one of said master wheels can be actuated by either one of said 80 members.

15. In a calculating machine, the combination of a pair of calculating keys, a single key mechanism adapted to be actuated upon the operating travel of either of said keys, means 85 for automatically releasing said mechanism when one of said keys has been operated downwardly so that said other key can be operated during the return travel of said first operated key, and means for preventing 90 a succeeding operation on either of said keys during their return travel.

16. In a calculating machine, a calculating key, an accounting shaft bearing a gear adapted to continuous movement during the 95 complete downward travel of said key, a member pivoted intermediate of its ends co-operable with said key and said shaft gear, there being a swivel support for the pivot of said member, and means whereby said 100 member is swung horizontally from co-operative engagement with said shaft gear upon completion of the downward stroke of said key.

17. In a calculating machine, a calculating 105 key, an accounting shaft bearing a gear adapted to continuous movement during the complete downward travel of said key, means for locking said shaft against movement, a member pivoted intermediate of its 110 ends co-operable with said key and said shaft gear, means carried by said key for forcing said member into engagement with said shaft gear, and means whereby said member is swung horizontally from co-operative 115 engagement with said shaft gear upon completion of the downward stroke of said key.

18. In a calculating machine, a series of calculating keys, a transmission shaft, a 120 transmitting member for each of said keys co-operable with said shaft, and a single key mechanism co-operable with each of said keys adapted to be actuated by each of said transmitting members on the downward 125 movement of any of said keys for preventing the remaining keys being actuated, said actuated transmitting member adapted to release said mechanism just before completion of the downward movement of the operated 130

key, thereby releasing the idle keys so that another calculating key can be operated upon completion of the downward stroke of the first operated key.

5 19. In a calculating machine, a calculating key, a transmission shaft, a transmitting member operable with said key and said shaft, a single key mechanism, and a locking pawl operable with said shaft and said 10 mechanism, said key during its downward travel adapted to actuate said mechanism thereby releasing said pawl from locking engagement with said shaft, said mechanism adapted to be released just before completion 15 of the downward movement of said key thereby actuating said pawl and locking said shaft.

20 20. In a calculating machine, a calculating key, a transmission shaft and a transmitting 20 member operable with said key and said shaft during the complete downward travel of said key, a guiding plate for one end of said transmitting member, and means provided on said key for forcing said transmitting member to one side of said guiding plate.

21 21. In a calculating machine, a calculating key, a transmission shaft and a transmitting member operable with said key and said 30 shaft during the complete downward travel of said key, a guiding plate for one end of said transmitting member, means provided on said key for forcing said transmitting member to one side of said guiding plate, 35 and a locking device adapted to be actuated by said transmitting member during the downward travel of said key.

22 22. In a calculating machine, a calculating key, a transmission shaft and a transmitting 40 member operable with said key and said shaft during the complete downward travel of said key, a guiding plate for one end of said transmitting member, means provided on said key for forcing said transmitting member to one side of said guiding plate, a locking device adapted to be actuated by said transmitting member during 45 the downward travel of said key, and means for preventing said transmitting member 50 from being moved downward during its upward travel on its return movement.

23 23. In a calculating machine, a pair of calculating keys, a transmitting member co-55 operable with each of said keys, a guiding member for each of said transmitting members, a locking device for preventing one of said members being moved downwardly when said other member is being moved downwardly, and a movable engaging member located on one side of each of said guiding members for preventing each of said transmitting members being returned downwardly on their upward travel.

24 24. In a calculating machine, a pair of 60 calculating keys, a transmitting member co-

operable with each of said keys, a guiding member for each of said transmitting members, a locking device for preventing one of said members being moved downwardly when said other member is being moved downwardly, means provided by each calculator key for engaging its respective transmitting member to one side of a respective guiding member and a movable engaging member located on one side of each of said guiding members for preventing said transmitting members from being returned downwardly on their upward travel.

25 25. In a calculating machine, the combination of a pair of calculating keys, transmitting means co-operable with each key, crowding members, a respective movable member for each key adapted to be moved into said crowding members when each key is separately operated, said crowding members and each respective movable member providing means for preventing actuation of one of said keys while said other key is being operated in one direction, and means provided whereby when one of said keys has been operated in one direction the respective movable member actuated thereby into said crowding members will be released from said crowding members immediately after the operated key has been actuated and before it has moved on its return stroke.

26 26. In a calculating machine, the combination of a pair of calculating keys, transmitting means co-operable with each key, crowding members, a respective movable member for each key adapted to be moved into said crowding members when each key is separately operated, said crowding members and each respective movable member providing means for preventing actuation of one of said keys while said other key is being operated in one direction, and means provided whereby when one of said keys has been operated in one direction the respective movable member actuated thereby into said crowding members will be released from said crowding members immediately after the operated key has been actuated so that the other key can be operated before the first operated key has been returned to its natural position.

27 27. In a calculating machine, a calculating key, a transmission gear, a segmental lever pivoted intermediate of its ends adapted to swing vertically and horizontally having one end operable with said key and its opposite end co-operable with said gear, means provided for withdrawing said lever from meshing with said gear, and vertical guiding means for the depressed end of said lever for the return travel thereof.

28 28. In a calculating machine, a calculating key, a transmission shaft bearing a gear, a transmitting member operable with said key and said shaft, a single key mechanism,

9
a shiftable bar bearing a locking pawl adapted to be actuated by said mechanism, said pawl being operable with the gear of said shaft, said key during its downward travel adapted to actuate said mechanism thereby releasing said pawl from locking engagement with said gear, and a reversing gear co-operable with said shaft adapted to be held against movement by the actuation of said bar which bears said locking pawl.

10
29. In a calculating machine, the combination of a pair of calculating keys, an accumulator to be actuated by the downward movement of said keys, a single key mechanism co-operable with each of said keys adapted to prevent one of said keys being operated while the other key is actuating said accumulator, said single key mechanism adapted to be released after the downward stroke of each key so that the inactive key can be operated during the return stroke of the operated key, and means for preventing a second operation on the operating key before it has been returned to its neutral position.

30. A calculating machine having an accumulator, numeral keys, means for transmitting motion from said numeral keys to said accumulator, and a single key mechanism for preventing two or more keys from actuating the accumulator at the same time, said mechanism adapted to be released automatically upon the completion of the operative stroke of a key so as to permit a second key to be actuated during the inoperative stroke of a key, and means for preventing a second operation on the operating key before it has been returned to its neutral position.

40
31. A calculating machine having an ac-

cumulator, numeral keys, means for transmitting movement from said numeral keys to said accumulator, each of said keys being adapted to be depressed from its normal position to actuate the accumulator, a series of key actuated cams each of which is operable by a respective one of said keys, and a key locking device including a series of yieldable abutments located adjacent to each other, a portion of each of said cams being adapted to travel between two of said yieldable abutments during the downward stroke of the keys with which the cam is associated so as to hold the other abutments so close to each other that another of the cams cannot be actuated, and means for moving each cam away from said abutments after the key with which the cam is associated has completed its operative stroke so as to permit a second cam to be actuated by its key during the return stroke of another key.

32. A calculating machine having an accumulator, numeral keys, means for transmitting movement from said numeral keys to said accumulator, each key being adapted to be depressed from its normal condition to actuate the accumulator and adapted to return without actuating the accumulator during the return stroke, and a single key mechanism for preventing a plurality of the keys from being depressed at the same time, said mechanism adapted to be released automatically after a key has completed its operative stroke so as to permit a second key to be operated during the return stroke of a key, and means for preventing a depressing operation of a key during its return stroke.
